UNITED STATES PATENT OFFICE

JOSEPH D. BELL, OF SAN FRANCISCO, CALIFORNIA

DAVENPORT BED

Application filed May 22, 1928. Serial No. 279,676.

This invention relates to a davenport bed of the type in which the folding bed frame is divided into three sections, two of which extend substantially vertically and forward from the back and the other of which is at the bottom of the first two sections and prevents the clothing from falling out of the folded bed frame.

One object of the present invention is to produce a davenport bed which will be of such a type as to reduce the length of the folding bed frames, and to bring them as compactly and close together as possible when folded and placed within the structure of the davenport frame.

Another object of the invention is to produce a bed frame of such a nature as to permit the end members of the bed frame to fold into the recessed portion of the angle iron forming the folding frame to reduce the thickness of the frame when folded into the frame of the davenport.

Another object of the invention is to provide the bed frame with a convenient lever to start the folding of the frame, thereby making the folding of the bed into the davenport frame an easier matter.

Another object of the present invention is to provide means whereby the thickness of the seat may be increased special frames being provided to let down the springs in the seat so as to increase their depth and thereby improve the quality of the seat.

Another object of the invention is to produce an overturning seat for davenport beds which will be so arranged that the yoke carried thereby will support the folding bed frame, both in the folded position, and in the extended position, the yoke carried by the seat being used first to lift the bed frame out of the davenport, and thereafter when overturned to support the bed frame at the proper elevation.

Another object of the invention is to provide a pair of crossed links for the support of the bed frame in the davenport frame which will hold the bed frame in a fixed position with respect to the davenport frame, and which links will at the same time cause the inner bed frame to be placed close against

the back of the davenport frame, thereby giving the most space for bed clothes when the bed is folded up.

Another object of the present invention is to cause the inner bed frame to move toward the middle bed frame to reduce the space taken up by the inner bed frame and at the same time to cause the outer bed frame to move back on the middle bed frame thereby compressing the bed clothing as the bed frame is folded into the davenport frame.

Another object of the present invention is to provide the middle bed frame with rollers which can be used to support the bed frame independently of the davenport frame, if desired, and which rollers in the user of the bed frame in the davenport frame will be positioned on the floor and thereby reduce the weight of material carried by the davenport frame itself, and at the same time reduce the danger of injury to carpets, etc., when the davenport frame is moved by reason of the fact that a part of the weight is carried by the rollers on the bed frame, and a part on the davenport frame thereby reducing the unit pressure of the rollers on the carpet in the different places.

Another object of the invention is to produce a special type of hinge for the davenport back, which hinge will permit the back to be lifted out of the way of the bed user while at the same time making it certain that the back will not fall down when lifted.

Another object of the invention is to so arrange the lever and associated parts for starting the closing of the bed frame as to cause the outer bed frame to slide inwardly on the middle frame, and thereby compress the bedding as well as reduce the space occupied by the extended frames.

Other objects of the invention will be apparent as the description proceeds.

An embodiment of the invention is shown in the accompanying drawings in which the same reference numeral is applied to the same portion throughout the several figures of the drawings and of which there may be modifications.

Figure 1 is a perspective view of the bed davenport with the bed frame extended and

the back turned up, a portion of the spring mattress frame being shown.

Figure 2 is a vertical sectional view of the davenport frame showing the bed frame 5 folded up therein, with the supporting wheels for the folding bed frame shown on the floor line.

Figure 3 is a view of the bed frame folded up as it is used for a roll about bed, straps 10 being indicated to hold the two end sections up when not in use, and

Figure 4 is a perspective view of one of the angle iron ends where the frame supporting yoke is pivotally connected therewith.

15 The davenport frame consists of the front bar 1 which is properly secured to two end bars 2 and 3 at its ends and which bars are connected at their rear ends to the two posts 4 and 5, end arm sections 6 and 7 completing the outer appearance of the davenport. A back section 8 is fixed to the back posts 4 and 5, and forms the back enclosure to the davenport.

20 On each of the posts 4 and 5 there is a bracket 9, which bracket has two links 10 and 11 pivotally connected thereto in such a manner as to permit the link 11 to stand vertically when the back 12 is raised to the position shown in Figure 1 ready for the use of the 25 frame as a bed. These two links 10 and 11, are in turn connected to a bar 13 which is rigidly secured to the back 12, one set of said bars, and one set of said links being used at each end of the back 12.

30 35 In order to hold the bed clothing and mattress up at the center of the bed there are two straps 14 and 15 which are connected to the front rail 1 and to the bottom of the back 8 extending horizontally of the davenport 40 frame and closely adjacent the floor.

The bed frame in this case consists of the inner section A, the middle section B, and the outer section C. The inner section A has the two longitudinally extending angle members 45 17 and 18, and the transverse member 19 connecting them. The middle section consists of the two side members 20 and 21, also angle members. The outer section consists of the two longitudinally extending members 22, 23 50 and the transverse section 24 connecting the two members 22, 23 at their outer ends.

The seat for the bed davenport is of the so called over-turning type, and is indicated at 55. It has legs 26, 27 which support it at its outer edge when over turned as shown in Figure 1, while it has the extension hinges 28, 29 which connect it to the front bar 1 of the davenport frame, and permit it to assume the 60 position shown in Figure 2.

65 The seat frame 25 is rectangular in shape and hollow to permit the placing therein of the necessary seat springs, and it is open at the bottom as indicated at 30, and has a plurality of strap yokes 31 for the support of certain 65 of the seat springs as indicated at 32, there

being such a number of the yokes 31 as is necessary to support the center springs of the seat, said yokes being covered over with a canvas or other cloth covering 32' to prevent the accumulation of dirt and dust inside the seat.

The center of the bed is supported in the extended position by means of a yoke 33, said yoke being pivotally connected to the seat along the front edge of the opening 30, (note 70 Figure 1) or as it appears in Figure 2, along the back edge of said opening, with the end of the yoke pivotally mounted in a bracket 34 under each side of the bed frame at the front end of the members 20, 21 respectively.

The outer bed section C is supported at its outer end by means of a conventional bed end 36, which bed end is connected to the bed frame C by means of the links 37, 38, 39 and 40, said bed ends being just narrow enough to 80 pass between the outer flanges of the member C, and short enough to pass inside the outer flange of the member 24 as shown in Figure 2, whereby the compactness of the folded bed is very much increased, the ends of the links 37 to 40 inclusive passing into notches in the 85 side members as indicated at 42, 43 of Figure 2.

The inner bed section A is supported by four crossed over links 44, 45, 46 and 47 from 90 the bottom members 2 and 3 of the davenport frame. The upper ends of these supporting links are pivotally connected to two plates 48, 49 in such a manner that when the bed section is 95 horizontally placed as shown in Figure 1 the links are crossed over each other slightly at the upper end, and are parallel with each other when the bed is folded to the position shown in Figure 2, for an object presently to be explained. The plates 48 and 49 are 100 fixedly attached to the outside of the angle members 17 and 18 respectively.

Now it will be seen that the side members 110 17 and 18 of the bed section A are slidably connected to two side plates 50, 51 which in turn are pivotally connected to the rear ends of the two bars forming the center section B. Each of the plates 50, 51 is slotted as indicated at 52 and 53 to receive pins 54, 55 which are secured to the edge of the members 17 115 and 18.

The bed frame members 22, 23 each have two pivots as indicated at 56, 56' which pivots are connected respectively to links 57 and 58, the other ends of said links being pivotally connected to the lifting lever 59 which is pivotally mounted on the frame member 20 at 60.

At the other end of the frame member 20 120 there is a lever 61 which is pivotally mounted on the frame member 20 at 62 and said lever is pivotally connected to a link 63 which link is also pivotally connected to the pins 54 and to a link 64 pivotally connected to the pin 65, which connects the side member 125

51 with the side member 20. A link 66 pivotally connects the short end of the lever 61 with a mid portion of the lever 59, and a link 67 connects the end of the lever 61 with a short L shaped leg 68 pivotally mounted on the member 22.

The object of the construction of the levers just mentioned is to cause the inner bed section to slide down about four or five inches while during the folding process the outer bed section is slideable toward the inner bed section about four or five inches thereby compressing the mattress and bed clothing within the bed frame, and reducing the size of the 15 davenport frame required to carry the bed frame. During the extending of the bed, the inner section is moved by the links longitudinally of itself, and the outer section is extended or moved outwardly longitudinally 20 of the center section, whereby the three sections are extended to alignment.

An examination of Figure 2 will show that the center bed section B when folded up is in a position so that the wheels 70, 71 used 25 at each end of the bed frame just barely touch the floor, and this same bed frame may, if desired, be used as a roll-about bed without any change other than the addition of the bed end shown at 72. The bed end 72 is substantially identical with the bed end 36, and is pivotally connected to the section 30 A in the same manner, but inasmuch as it is not used in the frame it is unnecessary for it to assume the close position allowed by the 35 notches in the edge of the members of the frame C.

When this bed frame is folded as shown in Figure 3, straps 73, 74 are used to secure the two upper ends of the bed frame together, 40 with the blankets and mattress between them, and when unfolded the legs 68 will be seen to turn down to the dotted line position shown in Figure 3 which brings the center of the bed to the same elevation as both ends.

45 When the bed frame is in the extended position, a part of the frame rises and a part of the frame lowers, so that it is in a substantially balanced condition, and it requires very little effort to lift it up to place it in the folded position shown in Figure 2, and similarly it requires very little effort to unfold it when in the position shown in Figure 2, the person using the bed simply pulling up on one of the legs 26 or 27, overturning 55 the seat and at the same time causing the bed frame to rise and advance to the position shown in Figure 1, and during all of the time the bed frame is being lifted from the position shown in Figure 2 to the extended position, the center of the bed frame is supported 60 by the yoke 33, first depending from the underside of the seat, and thereafter being supported above the seat by said yoke.

65 The seat 25 is provided with any suitable seat padding 25' which is suitably uphol-

stered and mounted over the springs within the seat frame.

In order to hold the bedding in a better condition, there is a spring cable 80 connected to a plate 81 which is in turn connected 70 to another cable 82, and to a third cable 84 which extends to the cross member 24 at the outer end of the bed. This construction holding up the bedding and mattress when the bed is folded. The usual spring fabric 85 being used to carry the bedding when the bed is extended as a bed. The cable 84 operates as a septum and keeps two persons from the center of the bed.

Having thus described my invention, what I desire to secure by Letters Patent of the United States is as follows, but modifications may be made in carrying out the invention as shown in the drawings and in the above particularly described form thereof, 85 within the purview of the annexed claims.

1. A davenport bed comprising a fixed frame, a seat, means by which the seat is overturnably mounted on the fixed frame, a bed frame consisting of three sections, means 90 pivotally connecting the sections by which they may be folded or extended to alignment, one end section having means by which it is extensible and the other end section having means by which it is slidably connected to the center section, means by which the bed is partially supported from the overturned seat when extended, and means to cause the extensible section to be extended and the other end section to slide outwardly on the center 95 section as the bed frame is unfolded.

2. A folding bed frame comprising three sections consisting of a center section and two end sections, means pivotally and slidably connecting the sections by which they may be folded or extended to alignment, and means including a series of links connected to said means to cause the two end sections 105 to move away from the center section when the bed frame is unfolded.

3. A folding bed frame comprising an outer section, a center section, and inner section, means pivotally and slidably connecting the sections by which they may be folded or extended to alignment and a series of 110 links connecting the several sections adapted to cause one of the sections to move longitudinally of itself to reduce the space occupied by the bed frame, and to cause the other section to move longitudinally of the center section to bring it closer to the opposite end section to reduce the space filled by the bed clothing.

4. A folding bed frame comprising three folding sections, means pivotally and slidably connecting the sections by which they may be folded or extended to alignment a plurality of links to cause one of the sections to move longitudinally of itself to reduce 115 the space occupied thereby, means to cause 120

the other end section to move longitudinally of the center section to compress the bedding carried by the bed frame, a pair of legs connected to end of the frame, and a folding 5 leg pivotally connected to the center section of the bed frame for holding the center frame at the same elevation as the ends of the bed frame.

5. A bed davenport comprising a davenport 10 port frame, an inner bed section, a center bed section and an outer bed section all having means by which they are pivotally and slidably connected together, an overturning seat pivotally connected to the center section 15 and adapted to be turned substantially 180° to lift the bed frame out of the davenport frame and to support it when extended, and means whereby the inner bed section will be moved longitudinally of itself to reduce the 20 space occupied thereby, and means to move the outer bed section toward the inner bed section to compress the bedding when the bed frame is folded.

6. A bed davenport comprising a davenport 25 port frame, a folding bed frame foldable thereinto comprising an inner section, a center section, and an outer section, means pivotally and slidably connecting said sections, links connecting the inner section pivotally 30 to the davenport frame to permit it to stand in a substantially vertical position or to extend horizontally, and other links pivotally connecting the inner bed section to the middle bed section to cause the relative movement 35 toward each other of the middle section and the inner section when the bed is folded, and the reverse movement when the bed is unfolded.

7. A bed davenport comprising a davenport 40 port frame, and a folding bed frame foldable thereinto comprising an inner section, a middle section and an outer section, means pivotally and slidably connecting said sections, links connecting said inner section 45 to the davenport frame to permit it to stand in a substantially vertical position, or to extend horizontally, and other links connecting the inner section to the middle section to cause the two sections to slide relatively toward each other when the bed is folded and to cause a reverse movement thereof when the bed is extended.

8. A bed davenport comprising a davenport 55 port frame and a folding bed frame slidable thereinto comprising an inner section, a middle section and an outer section, means pivotally and slidably connecting said sections, links connecting the inner section to the davenport frame, other links connecting the 60 middle section to the outer section so as to allow a pivotal movement of the outer section toward the middle section when the bed is folded, and a reverse movement when the bed is extended.

65 9. A bed davenport comprising a daven-

port frame, and a folding bed frame foldable thereinto comprising an inner section, a middle section and an outer section, means pivotally and slidably connecting said sections and means including links adapted to 70 cause two of said sections to slide toward each other when the bed is folded and other links to cause two of said sections to pivotally move toward each other at the same time.

In testimony whereof I have hereunto set my hand this 9th day of May, A. D. 1928.
